[57] ABSTRACT

Apparatus for compensation of right and left pincushion distortion comprising a closed magnetic circuit having a saturable magnetic core with right and left half portions symmetrical to one another and a branched portion defining an air gap and symmetrically arranged with respect to the right and left half portions. The branched portion can be centrally located in the core or can be disposed at opposite ends thereof. A pair of first and second windings are wound on each of the right and left half portions, the first windings of both pairs being connected in series so as to have the same winding directions in relation to the saturable magnetic core and being adopted for being connected to a vertical deflection circuit, whereas the second windings of both pairs are connected in series so as to have reverse winding directions in relation to the saturable magnetic core and are adapted for being connected to a horizontal deflection circuit.

APPARATUS FOR COMPENSATION OF RIGHT AND LEFT PINCUSHION DISTORTION

BACKGROUND

This invention relates to apparatus for the compensation of right and left pincushion distortion in a color television set.

In general, the raster in a color television set becomes larger in right and left pincushion distortion as the deflection angle of a Braun tube is increased. Conventionally, to compensate for these distortions, the transformer including an E I type saturable magnetic core has been used in such a manner that a horizontal deflection current is amplitude-modulated into a parabolic wave form so that the horizontal deflection current is maximum in amplitude at the middle of each vertical scanning period. Namely, as shown in FIG. 1, an E type magnetic core 1' and an I type magnetic core 2' are joined together to form a composite magnetic core of E I type, whose center leg portion 3' thereof is provided with a winding or coil 4', and whose opposite side leg portions 5a', 5b' are provided with respective windings or coils 6a', 6b', the coils 6a', 6b' being connected in series at a point 7'.

The operation of the resultant transformer is as follows:

Opposite terminals 8a', 8b' of the series connected coils 6a', 6b' are connected in series to a horizontal deflection coil (not illustrated) in an image receiving set and when a horizontal deflection current flows through the coils 6a', 6b', magnetic fluxes arising from the deflection current are generated as shown by the solid-line arrows 9a', 9b', and these fluxes 9a', 9b' are reversed in direction at the center leg portion 3' and hence oppose one another so that a net voltage (horizontal deflection voltage) based on these fluxes is not induced in the coil 4'. As, in this case, an electric current of a parabolic wave form having a vertical deflection frequency is passed, while superposed on a direct electric current, between the terminals of the coil 4', this current produces fluxes 10a', 10b' as shown in dotted lines which serves as a control current for changing the degree of magnetic saturation at the center leg portion 3' and at the opposite side leg portions 5a', 5b'. As a result thereof, the inductance of the coils 6a', 6b' viewed from the terminals 8a', 8b' is modulated and thereby the electric current flowing through the horizontal deflection coil is amplitude-modulated into a parabolic wave form with the frequency of vertical deflection.

When, in this case, the relation between the inductance presented in the coils 6a', 6b' and the control electric current is examined with the horizontal deflection current varied as a parameter, the relation is as shown in FIG. 2. Namely, a curve A is obtained when the horizontal deflection current is zero, a curve D when the current is of maximum value, and curves B, C when the current is of intermediate values. It can be seen from FIG. 2 that the inductance of the coils is modulated according to the parabolic wave forms of the control current in the cases of the curves A, B, and C but the inductance is substantially unmodulated in the case of the curve D. It is assumed that this is ascribable to the fact that the magnetic core at the opposite side leg portions approaches its saturated condition under the influence of the horizontal deflection cur-

rent. When, accordingly, a vertical direction raster on the Braun tube is viewed, a complete compensation of the pincushion distortions in the vicinity of right and left end portions is difficult. Since it is usual that a distortion compensation apparatus is so designed that it uses a case where the foregoing inductance change characteristic feature is linear as in the case of the curve B of FIG. 2, the horizontal deflection current is small in the vicinity of the raster center portion and an inductance change along the curve A is brought about, and as a result the distortion compensation becomes excessive and a distortion in the reverse direction is brought about at that portion. Thus, the result is that the raster, in the case of use of the conventional distortion compensation apparatus, is such that distortions remain as shown in FIG. 3.

SUMMARY OF THE INVENTION

An object of the present invention is to provide pincushion distortion compensation apparatus to overcome the foregoing deficiencies and in which apparatus the magnetic core is prevented from being saturated with the electric current of the horizontal deflection current coils while completely compensating right and left pincushion distortions.

For achieving this object, it can be first considered, that the horizontal deflection current coils 6a', 6b' are connected so as to be reverse in winding directions. In this case, however, the magnetic fluxes 9a', 9b' in FIG. 1 have the same directions at the center leg portion 3' and are additive thereat whereby a saturation phenomenon is rapidly produced at that portion so that the control current does not operate effectively. It can be also considered that the center leg portion 3' of the magnetic core is entirely removed and the coil 4' provided near the coils 6a', 6b' on the opposite side leg portions. In this case, however, the magnetic fluxes 9a', 9b' of the coils 6a', 6b' entirely negate one another and the coils 6a', 6b' become useless. The invention is predicated on the concept that it can be considered that, concerning the center leg portion 3' of the conventional apparatus wherein the winding directions of the coils 6a', 6b' are reversed, a desirable condition could be obtained between the existence and the non-existence of the same.

BRIEF DESCRIPTION OF THE DRAWING

FIG. 1 is a side elevation view of a conventional apparatus for compensation of pincushion distortion,

FIGS. 2 and 3 are diagrammatic illustrations showing characteristic features thereof,

FIG. 4 is a side elevation view of one embodiment of apparatus for compensation of pincushion distortion according to the invention,

FIG. 5 is a graphical diagram showing a characteristic feature of the same,

FIG. 6 is a graphical diagram showing a comparison between characteristic features of the conventional apparatus and that of the invention,

FIG. 7 is a side elevation view of a modified embodiment according to the invention,

FIG. 8 is a top plan view thereof,

FIG. 9 is a side sectional view, taken along the line IX-IX in FIG. 10, of another modified embodiment according to the invention, and

FIG. 10 is a top plan view thereof.

DETAILED DESCRIPTION

Referring to FIG. 4 which shows one embodiment of this invention, numeral 1 denotes a saturable magnetic core of a closed magnetic circuit comprising a circular ring composed of right and left semi-circular portions 1a, 1b symmetrical in form with respect to one another and numeral 2 denotes a diverged or branched magnetic core extending in the middle portion of the magnetic core 1 to define an air gap 3 between the magnetic core 1 and the diverged core 2 so as to increase the magnetic resistance of the diverged magnetic core 2. The right and left half portions 1a, 1b are provided, respectively, with a pair of first windings or coils 4a, 4b and a pair of second windings or coils 5a, 5b wound thereon. The first windings 4a, 4b are connected in series at a point 6 so as to be the same in winding directions in relation to the saturable magnetic core 1, and numerals 7a, 7b denote the opposite terminals thereof. The second windings 5a, 5b are connected in series at a point 8 so as to be reverse in their winding directions, and numerals 9a, 9b denote the opposite terminals thereof. The terminals 7a, 7b are connected to a vertical deflection circuit (not shown), and the terminals 9a, 9b are connected to a horizontal deflection circuit (not shown).

With this arrangement, the magnetic fluxes induced in the coils 4a, 4b by the horizontal deflection current flowing through the coils 5a, 5b are made to be reverse in direction, so that no horizontal deflection voltage component is generated in the coils 4a, 4b. When the vertical deflection current is small in value, the magnetic fluxes generated from the coils 4a, 4b are small and the magnetic core 1 is never magnetically saturated. However, in the condition when the vertical deflection current is increased and before the magnetic core 1 is saturated, the inductance of the coils 5a, 5b can be modulated as in the conventional apparatus. The magnetic flux passing through the center leg portion 2 by the electric current flowing through the coils 5a, 5b does not saturate the center leg portion 2, because the magnetic resistance is large due to the presence of air gap 3. When the relation between the inductance of the coils 5a, 5b and the vertical deflection current value is examined in substantially the same manner as in the conventional case, the result is as shown in FIG. 5. Therein, curves A - D refer to horizontal deflection current values of a magnitude corresponding to those in the case of FIG. 2. It can be noted from FIG. 5, however, that when the horizontal deflection current changes in value, there occurs only a slight difference in the modulation condition of the coil inductance so that the modulation by the control current is always effected properly. As regards the raster generated according to this invention, it is compared with a regular lattice pattern and a distortion thereof is obtained in percent as shown in FIG. 6. In this FIGURE, curve E is obtained by use of the conventional apparatus, and curve F is obtained by the embodiment of this invention. It can be appreciated from FIG. 6 that a distortion of about 5 percent is caused at the extreme end portions in the conventional case but it becomes 1.5 percent at most according to the invention. Thus, there is obtained an extremely good distortion compensation apparatus, according to this invention, while additionally, there is no special difficulty in the manufacturing

process and the operation is stable over long periods of time.

FIGS. 7 and 8 show a modified embodiment of this invention. Therein, a saturable magnetic core 101 of closed magnetic circuit type comprises right and left half portions 101a, 101b which are provided at their right and left outside portions with respective branched or diverged magnetic cores 102 having respective air gaps 103. In this embodiment, the composite magnetic core is composed of a pair of right and left hand drum type cores G, each having upper and lower circular flanges g with connecting stems, the cores being suitably cut at their flanges to form flat faces at which they are joined together to form the composite magnetic core with the saturable magnetic core 101 and the right and left symmetrical diverged magnetic cores 102, having the air gaps 103. In other respects, this embodiment is not significantly different from the previously described embodiment.

FIGS. 9 and 10 show another embodiment of the invention in which the saturable magnetic core 201 with right and left portions 201a, 201b is provided at its right and left outside portions with respective branch or diverged magnetic cores 202 having respective air gaps 203. This is substantially the same as the foregoing embodiments except that the composite magnetic core is constituted by a pair of upper and lower pot type cores H, joined together through a pair of right and left stems h.

What is claimed is:

1. Apparatus for compensation of right and left pin-cushion distortions comprising a closed magnetic circuit including a saturable magnetic core having right and left half portions symmetrical to one another and a branch portion defining an air gap and symmetrically arranged with respect to said right and left half portions, a pair of first and second windings on each of the right and left half portions, the first windings of both pairs being connected in series so as to have the same winding directions in relation to the saturable magnetic core and being adapted for being connected to a vertical deflection circuit, the second windings of both pairs being connected in series so as to have reverse winding directions in relation to the saturable magnetic core and being adapted for being connected to a horizontal deflection circuit.
2. Apparatus as claimed in claim 1 wherein said branched portion is centrally disposed with respect to said right and left half portions.
3. Apparatus as claimed in claim 1 wherein said right and left half portions have opposite outside ends, said branched portion comprising a respective branch section at each of said outside ends of said half portions.
4. Apparatus as claimed in claim 1 wherein said saturable magnetic core is in the form of a circular ring, said branched portion extending along a diameter thereof.
5. Apparatus as claimed in claim 1 wherein said magnetic core is constituted by a pair of right and left hand drum elements, each having a pair of upper and lower circular flanges and a connecting stem, each of the flanges of the drum elements being partly cut to form flat faces at which the drum elements are joined together.
6. Apparatus as claimed in claim 1 wherein said magnetic core is constituted by a pair of upper and lower pot type core elements with respective stems, said core elements being joined together through a pair of right and left stems.
